UNITED STATES PATENT OFFICE

172,060

TOOTHBRUSH HOLDER

Max Reich, London, England, assignor to Combex
Limited, London, England

Application August 31, 1953, Serial No. 26,636

Claims priority, application Great Britain
April 23, 1953

Term of patent 7 years

(Cl. D4—3)

To all whom it may concern:

Be it known that I, Max Reich, a British subject, have invented a new, original, and ornamental Design for a Toothbrush Holder, of which the following is a specification, reference being had to the accompanying drawings, forming part thereof.

I claim:

The ornamental design for a toothbrush holder, as shown.
